UNITED STATES PATENT OFFICE.

JACOB S. MEYER, OF PITTSBURGH, PENNSYLVANIA.

METHOD OF MAKING HAND BAGS AND PRODUCT THEREOF.

Application filed July 23, 1924. Serial No. 727,723.

To all whom it may concern:

Be it known that I, JACOB S. MEYER, residing at Pittsburgh, in the county of Allegheny and State of Pennsylvania, a citizen of the United States, have invented or discovered certain new and useful Improvements in Methods of Making Hand Bags and Product Thereof, of which the following is a specification.

10 My invention relates to improvements in the method of constructing hand bags, whereby a bag of simple structure may be produced, with advantages both in diminished cost of construction and in neatness of 15 appearance and serviceability. Invention is found also in product.

The invention is illustrated in the accompanying drawings, in which Fig. I shows diagrammatically and in perspective, 20 parts of the bag in the course of construction, and serves to illustrate how the method is performed. Fig. II is a view in perspective of the finished bag.

25 The sort of hand bags with which my invention has particularly to do are those formed of pliable material, the mouth rimmed with a frame of rigid material, and the frame being made in two parts hinged together, for opening and closing. 30 Ordinarily the bag is formed of leather, or of a substitute having similar properties, and the frame is formed of steel. It is with the particular construction of the frame and the method of securing the bag material to the frame that my invention has 35 to do.

40 The frame is formed, sometimes of flat strips, sometimes of strips of angular cross-section, sometimes of round rods, and the bag material is secured to it, sometimes by riveting, sometimes by inclosing the frame members in a hem sewed in the edge of the bag. I form my frame of flat strips of steel, and I so assemble it with the bag material that the bag material is in the completion of the frame autogenously secured to it.

45 Referring to Fig. I, a web of bag material—leather or its equivalent—is indicated at 1. 2 is a strip of steel of proper length, bent to channel form in cross-section, and closely enclosing the straight edge of the web of bag material. When these parts have so been assembled, in the relative positions described, and indicated by 50 full lines in Fig. I, the frame member 2 is

bent, and its ends turned to the dotted-line position, thus forming a U-shaped frame part, which is one half of the double hinged frame of the bag mouth. This bending is preferably done between dies in a bending press. In the operation of bending, the two strips are confined against free relative displacement and the overlying web of the channel-shaped steel strip is 60 stretched, relatively to the underlying web, the two webs are drawn closely one upon the other, and the web of bag material lying between is caught and securely clamped 65 between.

70 It will be observed that the operation as thus far described is performed upon an otherwise unshaped web of bag material. When two parts have so been shaped, they are brought together, their frame parts 75 articulated by hinge-pins 3, and their webs of bag material united by seams 4. A bottom for the bag may be shaped as desired. Incidentally, before or after assembly of the two halves a handle such as 5 80 and locking means such as 6, 7 may be applied in well-known manner. The application of the handle involves, ordinarily, 85 a riveting-through of the frame, as at 8, and of course such riveting or even additional riveting is not forbidden; but my invention involves the clasping of the substance of the bag wall between two webs 90 of metal drawn one toward the other by bending, as the primary and essential means 95 of securing these parts.

I have shown and described the strip of metal 2 as formed of one piece, bent transversely to the form of a narrow channel. Manifestly it is the opposite webs of this 95 channel which are essential to the practice of the invention. The interconnecting bend of the channel is desirable, in that it affords a smooth rim 9 for the mouth of the finished bag. But otherwise the interconnecting 100 bend is unnecessary, and the two webs may be disconnected strips, and in that form also my invention may be practiced.

The strip 2 of steel or other suitable metal will ordinarily receive its desired surface 105 finish, before being assembled with the web 1 of bag material. Such surface finish may vary widely in character; ordinarily, the metal is covered with a thin closely-adherent integument of leather or leather substitute.

110 The bag particularly illustrated in Fig. II is of the style or type commonly called

the Boston bag. Ordinarily the rim of a Boston bag is formed of a round rod of steel, enclosed in a hem of the bag material. The mouth of the bag closes by abutment 5 of the opposite rim members, and a strap and buckle secure the rim parts in closed position. The bag so closed is not weather-tight, and in continued service and in consequence of bending of the frame, the mouth 10 is apt to gape open even when secured in what is intended to be closed position. It will be observed of the bag illustrated in Fig. II and embodying, as I have explained, my invention, that it is a Boston bag, modified 15 with respect to the frame which forms its mouth. In closure the flat strips, applied after the manner described and in application embodying my invention, overlap in the closing of the bag, and make a 20 weather tight closure, which will not gape open.

I claim as my invention:

1. The method herein described of making the **U**-shaped member of a hand bag 25 with the bag material secured thereto, which consists in assembling a web of bag material between the opposite webs of a straight strip of metal channel-shaped in cross-section, bending the strip when assembled upon

the bag material transversely to **U**-shape between dies, and in so doing effecting at 30 the bend constriction of the outer web upon the inner and a finished union between the web of bag material and the frame.

2. A hand bag comprising in part a 35 **U**-shaped frame member formed of an initially straight channel-shaped strip, having the web of material which forms the main wall portion of the bag inserted within the channel of the frame member while the 40 frame member still is straight, the said straight frame member with the web of bag material in place in its channel having been bent between dies to the ultimate **U**-form, and in consequence of such bending the outer 45 wall of the channel having at the corners of the frame been constricted upon the inner wall with the web of bag material between, whereby the web of bag material is gripped between the opposite walls of the 50 channel and the parts integrated into a finished union.

In testimony whereof I have hereunto set my hand.

JACOB S. MEYER.
